UNITED STATES PATENT OFFICE.

WILLIAM C. PARSONS, OF CLEVELAND, OHIO, ASSIGNOR, BY MESNE ASSIGNMENTS, TO
THE D. R. C. WATER HEATER COMPANY, OF CLEVELAND, OHIO, A CORPORATION OF
OHIO.

WATER-HEATER.

1,215,844.

Specification of Letters Patent. Patented Feb. 13, 1917.

Application filed May 18, 1916. Serial No. 98,327.

To all whom it may concern:

Be it known that I, WILLIAM C. PARSONS, a citizen of the United States, residing at Cleveland, in the county of Cuyahoga and State of Ohio, have invented certain new and useful Improvements in Water-Heaters, of which the following is a specification.

This invention relates to water heaters of that type in which the water is caused to flow through a plurality of superposed sections confined in a casing, with a burner below, the sections being of that type having a central water connection therebetween, and curved passages communicating at opposite ends with said connection, through which passages the water flows in its course upwardly through the sections, the heater being the kind commonly employed for domestic purposes, although capable of other uses.

The object of the invention is to provide an improved heating element characterized by the novel construction of the water passages in order to produce a free and uninterrupted flow of water, and efficient heating spaces.

In the accompanying drawings,

Figure 1 is a side elevation of the heater, the casing being partly broken away.

Fig. 2 is a plan of one of the heating elements.

Fig. 3 is a section on the line 3-3 of Fig. 2.

Referring specifically to the drawings, 6 indicates the heater casing, 7 the burner at the bottom and 8 the top or cover. Within this casing are a series of superposed sections. Each section has a central hub part 9 with a partition 10 extending diagonally across the same and dividing it into inlet and outlet passages. These sections are connected together by short pipe connections 11 screwed into the opposite ends of the hub.

45 A pair of segmental water tubes or passages 12 are located at opposite sides of each section, and these are connected at their opposite ends to inwardly curved branch pipes or passages 13 which unite into single

passages 14 which open into the hub or central part, these branch pipes 13 forming flue spaces 16 therebetween. One pipe 14 opens above the partition 10 and the other below the same, whereby the water circulates from the lower central inlet to the hub 55 out through one pair of passages 13 and thence around through the passages 12 to the other pair of passages 13 and thence back to the outlet of the hub.

By extending the branches 13 in opposite 60 curved directions to the passages 12 the eddies produced by sharp angles at the junction of straight and curved passages are avoided, and the spaces between the branches 13 permit the flow of the products 65 of combustion therebetween, and in arranging the sections they will be staggered, that is, the segmental passages 12 of one section will be located above the spaces between the branches 13 of the section below. 70 In this way, the parts 14 will lap the openings 15 in the sections, and the segments 12 will lap the spaces 16 referred to, so that tortuous passages for the products of combustion are provided, and the full effect of 75 the heat is obtained. The casing fits rather closely around the sections, so that the heat is confined to the latter. The cooler water in its course enters the lower section and flows upwardly through the others in an 80 obvious manner.

What I claim as new is:

A water heater section comprising a central hub having a partition across the same, pipes 14 extending oppositely from said hub 85 and connected thereto respectively above and below the partition, segmental pipes 12 at the rim, and a pair of branch pipes 13 connecting each of the pipes 14 and the opposite ends of each of the segmental pipes, 90 said ends and the branch pipes being spaced apart to form outer flues for heat.

In testimony whereof, I do affix my signature in presence of two witnesses.

WILLIAM C. PARSONS.

Witnesses:

EMANUEL M. HERSKOWITS,
JOHN A. BOMMARDT.
